(57) **CLAIM**

The ornamental design for a cable wrap, as shown and described.

DESCRIPTION

FIG. 1 is an isometric front view of the new design for a cable wrap;

FIG. 2 is an isometric back view of the new design for a cable wrap;

FIG. 3 is a top view of the cable wrap;

FIG. 4 is a front view of the cable wrap;

FIG. 5 is a bottom view of the cable wrap;

FIG. 6 is a back view of the cable wrap;

FIG. 7 is a left side view of the cable wrap; and,

FIG. 8 is a right side view of the cable wrap.

The dashed lines are for illustration purposes only, and form no part of the claimed design.
